FIG. 1 is a perspective view of the stowable display system in a rotatable console in accordance with the present invention, with a display being depicted in a stowed orientation; FIG. 2 is a top view thereof with the display in the stowed orientation;

FIG. 3 is a right-side view thereof with the display in the stowed orientation;

FIG. 4 is a right-side view thereof with the display in a deployed orientation; and

FIG. 5 is a perspective view thereof with the display in a deployed orientation; and,

FIG. 6 is a perspective view of the stowable display system in a rotatable console in accordance with the present invention, with the display system rotated with respect to the console.

The broken lines shown in FIGS. 1-6 are for illustrative purposes as an environment and form no part of the claimed design.
